DESIGN FOR A RADIATOR GRILLE COVER UNIT FOR AUTOMOBILES

Willard L. Morrison, Lake Forest, Ill.

Application October 2, 1936, Serial No. 65,142

Term of patent 3½ years

To all whom it may concern:

Be it known that I, Willard L. Morrison, a citizen of the United States, residing at Lake Forest, in the county of Lake and State of Illinois, have invented a new, original, and ornamental Design for a Radiator Grille Cover Unit for Automobiles, of which the following is a specification, reference being had to the accompanying drawing, forming part thereof.

Fig. 1 is a front elevational view of one of the radiator grille cover units;

Fig. 2 is an edge view of the unit shown in Fig. 1 as seen on line 2—2 of Fig. 1.

I claim:

The ornamental design for a radiator grille cover unit for automobiles, substantially as shown.

WILLARD L. MORRISON.
